UNITED STATES PATENT OFFICE

PAUL MOUTON, OF PARIS, FRANCE, ASSIGNOR TO CHENEY BROTHERS, OF NEW YORK, N. Y.,
A CORPORATION OF CONNECTICUT

DESIGN FOR A TEXTILE FABRIC

Application filed September 16, 1932. Serial No. 44,864. Term of patent 3½ years.

To all whom it may concern:

Be it known that I, PAUL MOUTON, a citizen of France, residing at 29 Rue du Sentier-Paris, in the Republic of France, have invented a new, original, and ornamental Design for Textile Fabrics, of which the following is a specification, reference being had to the accompanying drawing, forming part thereof.

The figure is a plan view of a textile fabric, showing my new design. A single unit of my design is substantially comprised within the area defined by the indicating lines shown on the drawing.

I claim:

The ornamental design for a textile fabric, substantially as shown and described.

PAUL MOUTON.
